UNITED STATES PATENT OFFICE.

ALEXANDER O. TESCH, OF CHICAGO, ILLINOIS.

DIVING-CHAMBER FOR SUBMARINE OPERATIONS.

1,380,750.

Specification of Letters Patent. Patented June 7, 1921.

Application filed June 15, 1920. Serial No. 389,255.

To all whom it may concern:

Be it known that I, ALEXANDER O. TESCH, a citizen of the United States, and resident of Chicago, in the county of Cook and State 5 of Illinois, have invented certain new and useful Improvements in Diving-Chambers for Submarine Operations; and I do hereby declare that the following is a full, clear, and exact description thereof.

10 My invention relates to apparatus for submarine operations, and aims to generally improve the construction of such apparatus, whereby a desired operation may be accomplished quickly, efficiently and with the exertion of a minimum amount of effort on the part of the operator.

15 The invention resides in the novel features of construction, combinations and arrangements of parts, as will be hereinafter more fully described in connection with the accompanying drawings, and then particularly defined in the appended claims.

In the drawings:—

20 Figure 1 is a vertical section through an apparatus, constructed in accordance with my invention,

25 Fig. 2 is a section on the line 2—2 of Fig. 1,

30 Fig. 3 is a longitudinal section through one of the grappling devices; and

35 Fig. 4 is a section on the line 4—4 of Fig. 3.

Referring to the drawings in detail, 10 designates a chamber or vessel of any desired shape, and formed from any desired material, having sufficient strength to resist a heavy exterior pressure without distortion. Preferably this chamber is of substantially cylindrical shape, being closed at its upper

40 and lower ends by heads 11 and 12, respectively, and provided with a flattened side 13 to accommodate devices which will be referred to more particularly hereinafter. The upper head 11 is provided with a suitably closed manhole 14 to permit access to the interior of the chamber, and suitable cable connections 15 are provided whereby the chamber may be lowered into or raised

45 from the water, while to stabilize the chamber and cause it to sink, I attach thereto weights 16. Internally of the chamber, are provided suitable air-producing and purifying devices 17, and in the side and end walls of the chamber, are provided any desired

50 number of windows and light-projecting

devices 18, whereby an operator within the chamber may properly navigate and control the apparatus. Safety devices in the form of plates 19 are provided to be swung over the window and light-projecting openings to 60 exclude water from the chamber in the event of breakage of the transparent material covering said openings.

I have provided propelling and steering means operable from the interior of the 65 chamber, whereby the apparatus when submerged, may be navigated at the will of its occupants and independently of persons or devices upon the surface. The propelling means consists of a plurality of propellers 70 20 arranged exteriorly of the chamber and journaled on shafts which extend into the chamber and have fixed thereto miter gears 21. Meshing with these gears are similar gears 22 on a shaft 23, which is journaled in 75 bearings projecting from the side wall of the chamber. An additional gear 24 is provided on the shaft 23, and this gear meshes with a gear 25 on a horizontal motor shaft 26. Thus when the shaft 26 is rotated its 80 movement will be transmitted through the shafts and gears just described to the propellers.

The steering mechanism consists of one or more rudders 27 on a shaft 28 journaled in 85 bearings 29 secured to the outside of the chamber. A gear 30 on the shaft 28 meshes with a gear 31 on a shaft which extends into the chamber, and this latter shaft has fixed thereto a hand wheel 32 which, upon rotation, will swing the rudders as will be apparent.

A motor 33 is provided for driving the shaft 26, and said shaft in addition to the gear 25, is provided with a second gear 34 95 which meshes with a gear 35 on a stub shaft 36 journaled in a bearing block 38 secured to a central portion of the upper head 11. Also meshing with the gear 35 is a gear 38 on a horizontal shaft 39, which is journaled in the block 37 and in a bearing carried by the side wall of the chamber. This latter shaft also carries a gear 40 meshing with a gear 41 on a vertical shaft 42, said shaft 42 being journaled in suitable bearings carried 100 by the side wall of the chamber and being provided with additional gears 43 and 44 meshing with gears 45 and 46, respectively, on the inner ends of brush shafts which extend through the side wall of the chamber 110

and carry at their outer ends, exteriorly of the chamber, brushes 47 and 48, respectively. Thus power may be transmitted from the motor through the shafts and gears just described to rotate the brushes for any desired purpose, as for instance, cleaning the side of a sunken ship. Clutch members, conventionally illustrated at 49, may be provided on the shafts 26 and 39 in order 10 that the motor may be allowed to run free without operating either the propellers or the brushes and in order that either the brushes or propellers may be operated independently with respect to each other. If 15 desired, shafts other than shaft 39 may be operated from the gear 35 for imparting motion to the chamber or other devices associated with the apparatus. A pair of such shafts are illustrated at 50 in Fig. 2 of the 20 drawings, but the devices they may operate, have not been shown.

From the foregoing, it will be observed that the chamber may be navigated to any desired position, while submerged by an operator within the chamber, and that when brought into juxtaposition, as for instance with the side of a sunken ship, the brushes 47 and 48 may be operated to clean accumulated matter therefrom.

30 It is desirable that an apparatus such as the present be equipped with grappling devices, indicated at A, operable from the interior of the chamber to grip objects exteriorly thereof in order to raise such objects 35 to the surface or to move them while submerged, and I have provided an improved grapple for such purposes, constructed as shown in Fig. 3, which is as follows:

Through an opening in a wall of the 40 chamber I pass a flanged tube 51 and secure it rigidly to the chamber by passing bolts through the flange and the wall of the chamber. This tube is interiorly screw-threaded throughout a portion of its length, and passing therethrough, is a second tube 52 exteriorly screw-threaded and engaging the interior threads of the first tube. Tube 52 projects beyond the outer end of tube 51, and is provided with a plurality of pairs of 45 ears through which pass pins 53 having journaled thereon toothed segments 54 to which are secured curved gripping jaws 55. Passing through the tube 52 is an exteriorly threaded sleeve 56, the threads of which 50 mesh with the teeth of segments 54, whereby rotation of said sleeve relative to the tube 52, will swing the jaws toward or away from each other to either grip or release an object 55 therebetween. Angular adjustment or movement of the jaws toward and away from the 60 chamber may be accomplished by rotating the tube 52 because of its threaded engagement with the fixed tube 51. A crank 57 on the tube 52 and a similar crank 58 on the 65 sleeve 56 provide means interiorly of the

chamber, whereby said tube and sleeve may be conveniently rotated.

Passing through the sleeve 56 is a rod or shaft 59 which is threaded at its outer end to receive a hook 60, by which the apparatus is secured to a ship. In the drawings, I have shown a hook or the like provided at one end with an internal threaded opening suspended by a cable 62 from a ship. When the shaft 59 is secured to this, 75 the hook is first gotten into position to receive the threaded end of the shaft by the grappling jaws 55, after which the shaft is rotated. If desired, a tool or the like may be secured to the shaft 59 in place of the 80 hook and operated for various purposes either independently or in conjunction with the gripping jaws 55.

Packing glands are provided between the shaft 59 and sleeve 56, between the sleeve 85 and the tube 52, and between the tube 52 and tube 51, in order to prevent leakage of water around these parts of the apparatus, and if desired, a coil spring 61 may be interposed between the inner end of sleeve 56, 90 and a collar on the shaft 59 in order that the tube 60 may be permitted to yield outwardly slightly to better engage an object to be operated upon.

I have disclosed my invention in the best 95 form known to me at present, but as the several parts of the device are subject to change, by the employment of ordinary mechanical skill, I limit myself to the use and development of my invention, only by the 100 terms of the appended claims.

Having thus fully described my invention, what I claim as new, and desire to secure by Letters Patent, is:—

1. In an apparatus of the character described, a grapple including relatively movable gripping jaws, a rotary sleeve for operating said jaws, a rod yieldably held within said sleeve and adapted to receive on one end a tool, said tool to operate in conjunction with said gripping jaws. 105

2. A gripping device for diving bells comprising an interiorly threaded tube, an exteriorly threaded tube arranged within said fixed tube with its threads meshing with the threads of said fixed tube, gripping jaws including toothed segments pivoted to said exteriorly threaded tube, an exteriorly threaded sleeve within said exteriorly threaded tube, the threads of said sleeve 110 meshing with the teeth of said segments, means for rotating said sleeve, means for rotating said exteriorly threaded tube, a shaft passing through the said sleeve, and a tool carried by said shaft. 115

In testimony that I claim the foregoing I have hereunto set my hand at Chicago, in the county of Cook, and State of Illinois.
